GEORGE WASHINGTON OTTERSON, OF SEATTLE, WASHINGTON.

SETTLING-BED.

1,344,710.

Specification of Letters Patent. Patented June 29, 1920.

Continuation of application Serial No. 240,441, filed June 17, 1918. Patent No. 1,295,056, dated February 18, 1919. This application filed January 28, 1919. Serial No. 273,543.

To all whom it may concern:

Be it known that I, GEORGE W. OTTERSON, a citizen of the United States, and resident of Seattle, in the county of King and State 5 of Washington, have invented a new and useful Settling-Bed, of which the following is a specification.

The invention relates to settling beds, and particularly to settling beds employed in 10 connection with apparatus for cleaning sewer basins and the like, such as shown in U. S. Patent No. 1,295,056, Feb. 18, 1919, and application Serial No. 240,441, filed June 17, 1918, of which the present application 15 is a continuation, and U. S. Patent No. 1,327,211 of January 6, 1920, of which this application is a continuation in part. One of the objects of the invention is to provide a simple, compact and effective 20 form of settling bed. Another object is to provide a portable, vehicle-carried bed, baffled to cause the water to throw down its solids and freely dischargeable by tilting. These and other objects and features 25 of the invention will become apparent as the specification proceeds.

In the accompanying drawings forming a part hereof:

Figure 1 is a side elevation of a traveling 30 sewer basin cleaning apparatus embodying the invention, the settling bed tank body being shown partly in elevation and partly in vertical longitudinal section in two different planes, and dotted lines being used to 35 show the tank partly tilted for dumping;

Fig. 2 is a plan view;

Fig. 3 is a transverse vertical section on the line 3—3 of Fig. 2; and

Fig. 4 is a rear elevation of the body, 40 showing the tail-gate.

In these views the settling bed 1 forms a tank body upon a motor vehicle 2. In addition the vehicle carries a hydraulic ejector elevator adapted to be let down into and 45 raised from a catch-basin 3, the said elevator comprising an ejector 4 and pressure and discharge lines 5 and 6. The pressure line 5 leads from the outlet of a pump 7, and the discharge line 6 terminates in a 50 spout 8 to deliver the mixed stream of liquid and solids from the basin into the forward part of the settling bed. A water outlet 9 also at the forward part of the bed connects through an automatic make 55 and break joint 10 with the intake pipe 11 of the pump. The outlet 10 is at or near the

bottom of the tank, and above it, through the front wall, a certain distance below the top, is an overflow opening 12, from which water is returned through a pipe or hose 60 13 to the basin. The outlets 9 and 12 are provided with flap valves 14 and 15 by which they can be opened and closed at will, the valves having flexible operating connections 16 and 17 extending to the top of the 65 tank.

The settling bed is a substantially horizontal, rectangular tank, covered or not, and open to the pressure of the atmosphere. A longitudinal, vertical partition 18 extends 70 in its interior near one of the side walls, from the front wall to within a short distance of the tail-gate 19, forming a substantially clear water gutter 20. The outlet 10 to the pump and the overflow 12 both open 75 out of this gutter, while the spout 8 is arranged or adapted to discharge into the main interior of the tank at the opposite side of the partition.

The said main interior or settling space of 80 the tank contains a series of transverse baffles 21 and 22, forming intervening settling compartments. The baffles 21, of which three are shown, form partitions across the main interior, which are substantially unbroken except for large flow openings 23 in their upper portions. These openings are located alternately adjacent the partition 18 and remote therefrom, so as to compel the water in passing rearward to pursue a circuitous course, as indicated by the arrows. The last baffle 22 has its upper half, more or 85 less, pierced with a multiplicity of small sieve openings 24. An additional low and narrow baffle 25 is placed at the rear entrance of the gutter 20. The baffles 21 and 22 are hung swingingly on top cross-rods 26, and the baffle 25 is similarly hung on a rod 27.

The settling bed body is pivoted toward 100 the rear on the frame of the vehicle, as indicated at 28, so as to be tiltable for rear dumping by means 29 such as are commonly provided on dumping trucks.

The tail-gate 19 is also top hinged at 30, 105 and is held tight shut by releasable clamps 31, suitable gasket means (not shown) being provided to prevent leakage. Additional holding is effected by dogs 32 bearing upon the back of the gate at the bottom, these 110 dogs projecting from a transverse rock-shaft 33 mounted on the under part of the

tank. An operating rod 34 extends from a crank-arm 35 on this shaft to a forward hand lever 36, which coöperates with an ordinary serrated sector 37 to hold the dogs 5 hard against the gate.

The baffles and the partition 22 are preferably connected with a top frame 38, enabling all the interior parts to be lifted out so that the tank can be used for cargo-carrying purposes. The said frame is bolted at 10 39 to angles 40 on the upper longitudinal edges of the body, and its side members are apertured to receive the ends of the hinge rods 26. An angle 41 on the upper edge of 15 the partition 18 is bolted at 42 to cross-members 43 of the frame, and other bolts 44 detachably secure a bottom angle 45 of the partition to the floor. Splash plates 46 and 47 are disposed over the top marginal parts 20 of the tank, the side plates 46 being preferably carried by the removable frame and the end plates 47 secured to the body.

In operation, the stream of liquid and solids to be separated is delivered into the 25 forward part of the main interior of the tank. The water flows rearward from compartment to compartment, through the staggered upper openings in the baffles 21, dropping its solids in these compartments, 30 and then through the screen openings in the baffle 18, by which floating bodies are removed. From the last compartment, between the baffle 22 and the tail-gate, the substantially clear water enters the rear end 35 of the gutter 20, where the additional baffle 25 is placed as a further obstacle to solids reaching the outlet. From the forward part of the gutter the water is withdrawn by the pump 7 through the outlet 10, 40 and forced downward through the pressure line 5 to maintain the ejector jet in the basin. At the conclusion of the operation the water not needed for priming the pump at the basin next visited is run back through 45 the overflow line 13 to the basin. When the settling bed is full of solids, the vehicle proceeds to a place of discharge, the tail-gate is unfastened, and the body is upturned. The baffles being free to swing rearward relatively to the body, the contents slide out beneath them, and the bed is thus expeditiously 50 emptied of its deposits. In unfastening the tail-gate, the attendant first releases the clamps 31, and then goes forward 55 and unlocks the lever 34, thereby releasing the dogs 30 and permitting the gate to swing open.

What I claim as new is:

1. In a portable settling-bed, the combination with a vehicle, of a tight tank tiltably mounted thereon for rear dumping, transverse baffles with openings for passage of water swingingly supported in the tank and forming a plurality of settling chambers, 60 means for delivering a mixed stream of liq- 65 uid and solids into one of the compartments, and a water outlet communicating with a remote compartment.

2. In a portable settling-bed, the combination with a vehicle, of a tight tank tiltably 70 mounted thereon for rear dumping, a longitudinal partition in the tank close to one of its side walls forming a gutter communicating at one end with the main body of the interior, and transverse baffles swingingly 75 supported and extending from said partition to the opposite side of the tank forming a plurality of settling chambers in the main body of the tank.

3. A settling bed comprising a tight approximately horizontal rectangular tank having a partition close to one of its side walls forming a gutter communicating at one end with the main body of the interior of the tank, a water outlet from the remote 80 part of the said gutter, means for delivering a mixed stream into the main body of the tank, and transverse baffles forming settling chambers in the main body of the tank.

4. In a settling bed, the combination of a 90 tight approximately horizontal rectangular tank, a partition close to one of the side walls of the tank forming a relatively clear water gutter communicating at one end with the main interior of the tank and having an 95 outlet toward its opposite end, and transverse baffles forming settling chambers in the main interior of the tank having flow openings in their upper portions located alternately adjacent the partition and remote 100 therefrom.

5. In a settling bed, the combination of a tight approximately horizontal rectangular tank, a partition close to one of the side walls of the tank forming a relatively clear 105 water gutter communicating at one end with the main interior of the tank and having an outlet toward its opposite end, transverse baffles forming settling chambers in the main interior of the tank having flow openings in 110 their upper portions located alternately adjacent the partition and remote therefrom, and a terminal baffle provided with small sieve openings.

6. A portable settling bed comprising a 115 tight substantially horizontal oblong tank vehicle body having a longitudinal partition near one side forming a relatively clear water gutter open at one end to the general interior of the tank, baffles forming settling 120 chambers in said general interior, means for delivering a mixed stream into the baffled part of the tank, an outlet in the lower part of said gutter near its closed end, and a valve for opening and closing said outlet.

7. In apparatus of the class described, a settling tank, a support for the tank, means for hinging said tank on said support whereby said tank can be tilted for dumping purposes, a tail gate for the tank adapted to be 130

- opened in dumping, a swinging partition within the tank dividing the same into chambers for the separation of the liquid and solids and adapted to permit flow from one chamber to the other, means for delivering the solid and liquid material into one chamber, means for drawing off the liquid from another chamber as it separates from the solids and passes through the partition, and means for hingedly mounting said partition at the top to swing on a transverse axis whereby as the tank is elevated to dump the partition will tend to maintain a vertical position and thereby allow the separated material from both compartments to be discharged through the discharge end of the tank.

8. In apparatus of the class described, a settling tank, a support for the tank, means

for hinging said tank on said support whereby said tank can be tilted for dumping purposes, a swinging partition within the tank dividing the same into chambers for the separation of the liquid and solids and adapted to permit flow from one chamber to the other, means for delivering the solid and liquid material into one chamber, means for drawing off the liquid from another chamber as it separates from the solids and passes through the partition, and means for hingedly mounting said partition at the top to swing on a transverse axis whereby as the tank is elevated to dump the partition will tend to maintain a vertical position and thereby allow the separated material from both compartments to be discharged through the discharge end of the tank.

GEORGE WASHINGTON OTTERSON.
